UNITED STATES PATENT OFFICE

141,962

DESIGN FOR A CLAMP

Irvin Knobel, Osseo, Minn.

Application March 8, 1945, Serial No. 118,361

Term of patent 7 years

(Cl. D17—6)

To all whom it may concern:

Be it known that I, Irvin Knobel, a citizen of the United States, residing at Osseo, in the county of Hennepin and State of Minnesota, have invented a new, original, and ornamental Design for a Clamp, of which the following is a specification, reference being had to the accompanying drawing, forming part thereof.

Figs. 1 and 2 are side elevational views of a

clamp in closed and open positions respectively, showing my new design.

Fig. 3 is a top plan view of the clamp.

Fig. 4 is a bottom plan view thereof and

Fig. 5 is a front elevational view of the clamp.

I claim:

The ornamental design for a clamp, substantially as shown.

IRVIN KNOBEL.
